THEODORUS S. BAILEY, OF QUINCY, MASSACHUSETTS, ASSIGNOR TO ELECTRIC BOAT COMPANY, OF NEW YORK, N. Y., A CORPORATION OF NEW JERSEY.

CONNING MECHANISM FOR SUBMARINE BOATS.

1,037,191.

Specification of Letters Patent.

Patented Sept. 3, 1912.

Application filed February 26, 1908. Serial No. 417,955.

To all whom it may concern:

Be it known that I, THEODORUS S. BAILEY, a citizen of the United States, residing at Quincy, county of Norfolk, and State of Massachusetts, have invented certain new and useful Improvements in Conning Mechanism for Submarine Boats; and I do hereby declare the following to be a full, clear, and exact description of the invention, 10 such as will enable others skilled in the art to which it appertains to make and use the same.

The object of the invention is to provide a periscope for submarine vessels, in which 15 the periscope tube as a whole may be raised or lowered at will and can be rotated on a vertical axis to scan the entire horizon.

The character of the improved mechanism in its details will be understood from the 20 following description and the accompanying drawings, in which the same reference characters refer to like parts throughout.

In the drawings, Figure 1 is a vertical longitudinal section through the axis of the 25 vessel showing the conning tower and adjacent parts of a submarine boat of standard construction showing the improved periscope in place; Fig. 2 is a central vertical section of the periscope tube and associated 30 parts; Fig. 3 is a sectional plan on the line 3—3 of Fig. 2; Fig. 4 is a sectional plan on the line 4—4 of Fig. 2, and Fig. 5 is a sectional plan on the line 5—5 of Fig. 2.

The hull A of the boat has an upstanding 35 conning tower B of known construction. In the particular embodiment shown the periscope passes through the conning tower and through an upstanding periscope support B', but the periscope may readily be 40 fitted outside the tower if proper provision is made for supporting the parts. Secured in the periscope support B' and extending down through the conning tower and suitably supported at its base is a casing a constituting a cylinder within which the piston 45 hereinafter described moves, and having a stuffing box at each end, through which the periscope tube b passes. The periscope tube is provided at the upper end with an object

50 lens c of standard type and at its lower end with the ordinary telescopic eye-piece d. In the central portion of the tube is the middle lens e, which, in the particular form shown, is mounted within the piston, hereinafter 55 mentioned, but may be otherwise located

in the tube and supported in any suitable way to give the desired effect in transmitting the light rays down the tube in the proper way. Surrounding the periscope tube within the casing a and suitably attached to the tube is a piston f. Mounted in a suitable bracket (as indicated at g in Fig. 5) and held thereby in fixed position, is a gear wheel h meshing with the screw i, these parts being of the now well known construction for rotating the periscope tube. In order, however, that the periscope tube may be raised and lowered through this stationary gear the gear is not secured to the periscope tube, but is adapted to be clutched thereto by the mechanism illustrated particularly in Figs. 2, 4 and 5, from which it will be seen that the inner surface of the gear h is shaped like the frustum of a cone and is screw-threaded on its upper portion, 70 and entering the space between the periscope tube and the inner surface of the gear h is the hub of hand wheel k, which is screw-threaded to engage the screw threads on the inner surface of the gear h and is tapered 75 and split at its lower part so that when the hand wheel k is screwed down the tapered portions of the hub wedge between the periscope tube and the inner surface of the gear h to clutch the gear to the tube. This clutch 80 mechanism has been adopted as a convenient form, but it will be understood that any other suitable clutch may be substituted therefor. When the clutch is locked the periscope tube cannot be raised or lowered, 85 but it may be rotated by turning the screw i.

For the purpose of raising and lowering the periscope when it is unclutched the following mechanism is provided. Communicating with the upper end of the casing a is a pipe l in which is connected a hand pump m and which communicates with an oil tank n. The pump section is bridged by a by-pass o controlled by a valve o'. Communicating with the lower end of the cylinder a is a pipe p in which is connected a hand pump q and which communicates with the oil tank r. The pipe p is bridged by a by-pass s containing a valve s'.

It will be observed that the stuffing box 105 at the upper end of the periscope tube is contained in a casing t which engages the upper end of the casing a and may be removed therefrom so that by removing from the lower end of the periscope tube the hori- 110

zontally extending section containing the eye-piece the tube may be removed, with its piston, from the casing *a* without disassembling the casing.

- 5 The operation of the parts is as follows, assuming that at the start the periscope is in its lowered position: In this position, since the periscope tube is not in service at that time, the clutch mechanism is in position to 10 unclutch the tube from the gear *h*. To raise the periscope the valve *o'* in the bypass *o* is opened and the valve *s'* in bypass *s* is closed. Thereupon by operating the hand pump *q* oil is pumped from the tank *r* 15 through pipe *p* beneath the piston *f* in casing *a*, thereby elevating the periscope to the desired position, during which movement the oil above the piston flows out through pipe *l*, bypass *o*, valve *o'*, into the tank *n*. 20 When the periscope tube has been sufficiently elevated the hand wheel *k* is operated to clutch the tube and the gear *h*, whereupon the tube may be rotated by turning the screw *i* to scan the entire field of 25 vision. When it is desired to lower the tube the hand wheel *k* is turned to unclutch the parts and the valve *o'* is closed and the valve *s'* opened and the pump *m* is operated to introduce the oil above the piston, forcing out the oil beneath the piston into 30 tank *r*.

By using oil as the actuating fluid, certain important advantages are attained in that any liability to freezing is avoided and 35 particularly the parts are well lubricated so that the periscope tube slides easily through the stuffing boxes at each end. Furthermore, the oil protects the packing in the stuffing box from corrosion by the salt 40 water and serves as a fluid lock to lock the periscope tube in any desired position and to cushion its movement. It will be understood, however, that any other fluid may be used for the mere purpose of elevating and 45 lowering the periscope. It will also be understood that instead of using hand pumps or power pumps for pumping the fluid, the fluid may be retained in tanks under air pressure and controlled in the proper way 50 to elevate and lower the periscope tube.

What I claim is:—

1. In conning mechanism for submarine boats, the combination with a periscope tube carrying at its upper end an object lens and 55 at its lower end an eye-piece, of a piston

connected to said tube between the object-lens and eye-piece, a casing in which said piston moves, and means for supplying motive fluid to said piston at will to raise the periscope tube bodily; substantially as described. 60

2. In conning mechanism for submarine boats, the combination with a periscope tube carrying at its upper end an object lens and at its lower end an eye-piece, of a casing surrounding said tube between the object lens and eye-piece, a piston on the tube within the casing, and means for supplying motive fluid to the casing at either side of the piston at will to raise or lower the periscope 65 tube bodily; substantially as described. 70

3. In conning mechanism for submarine boats, a periscope tube carrying at its upper end an object lens and at its lower end an eye-piece, a casing surrounding said tube between the object-lens and eye-piece, and a piston on the tube within the casing, said casing projecting outside of the boat so that it is exposed to the sea water during submergence, and having at its exposed end a 75 closure containing a stuffing box through which the tube projects from within the boat to the outside thereof, in combination with a source of oil supply, connections between the two ends of the casing and the 80 said source, and means for withdrawing the oil from one side of the piston and supplying it to the other side to raise or lower the periscope tube bodily, substantially as described. 85

4. In conning mechanism for submarine boats, the combination with a periscope tube carrying at its upper end an object lens and at its lower end an eye-piece, a casing surrounding said tube between the object lens and eye-piece, a piston on the tube within the casing, and means for supplying motive fluid to the casing at will to raise the periscope tube bodily, of gearing for rotating the tube on its vertical axis and a clutch between the gearing and tube, whereby the 95 gearing may be released from the tube when the tube is to be raised or lowered; substantially as described. 00

In testimony whereof I affix my signature, in presence of two witnesses.

THEODORUS S. BAILEY.
